Howson & Howson

UNITED STATES PATENT OFFICE

THEODORE C. SMITH, OF PHILADELPHIA, PENNSYLVANIA

CONNECTER SOCKET FOR ELECTRIC PLUGS

Application filed September 3, 1921. Serial No. 498,345.

My invention relates to new and useful improvements in a connector socket for electric plugs, and relates to devices of this character which are carried at the ends of flexible leads 5 or cords for cooperation with contact members or terminals of said irons, electric stoves and other similar electrical appliances and is adapted to fit differently shaped terminals such as round, flat or square as well as terminals of different sizes.

Another object of the invention is to provide a socket contact member which when in engagement with a complementary contact member or terminal will engage the same 15 along the entire length of that portion of the complementary contact member or terminal which is within the socket contact member thereby greatly increasing the contact surface over such devices in use at the present 20 time, it being understood that generally two of such socket contact members are located within a casing or housing of insulating material in such manner as to permit limited movements of said socket contact members 25 for the reception of terminal members which may be out of parallelism or which have variable distances between centers.

Another object of the invention is to provide a socket contact member consisting of 30 three principal parts which are movable laterally toward and away from each other into parallelism.

Another object of the invention is to provide three separate contact elements all of 35 which cooperate and to provide resilient means superimposed thereon to unite the parts and normally force them toward each other.

A further object of the invention is to provide a socket contact member in the form of 40 a clamp having a virtually stationary element and two coacting movable elements the latter being fulcrumed on the former so as to have a limited sliding hinge like movement 45 whereby the contact surfaces of said elements will cooperate with terminals of different shapes thus making the socket contact member universal in its application to such terminals.

50 Another principal object of the invention is

to produce a contact member in which the electrical conducting elements are of one metal preferably high in electrical conductivity, such as copper or brass and a spring element of different metal preferably high in 55 spring quality.

This is a new and novel construction of a contact member and very important due to the fact that such articles require constant spring pressure on contact and the known 60 metals which are high in electrical conductivity are low in spring action. The metals high in electrical conductivity may have stiffness, but not spring qualities and this stiffness may be lost by the annealing process of 65 heat generated by the electrical device such as an electrical iron on which these are used. A metal high in spring quality such as tool steel spring tempered will not be annealed by the lower heat of such electrical device.

Another principal object of the invention 70 is to provide a contact member in which the electrical conducting element is moved into contact position rather than bent into contact position.

Another principal object of the invention 75 is to provide a contact member in which the axes of movement of the contact and spring elements lie in parallel position with the axis of the coacting contact member. This will produce contact on the full length of an inserted coacting contact member even though the contact member be of different shapes or sizes.

Still another object of the invention is to 80 provide a jack-receiving socket, wherein the axis of movement of the contact surface of one of the contact elements is approximately parallel to the flat portion of said contact surface, or is approximately parallel to the axis 85 of insertion of the inserted jack.

A still further object of the invention is 90 to provide an integral nut housing as a part of the socket contact member thereby supplying the desired threaded surface for a binding screw without increasing the thickness of the metal from which the socket contact member is produced.

Other objects and applications of my 95 invention, as well as details of construction and 100

operation, whereby my invention may be practiced, will be apparent more fully hereinafter, when taken in connection with the accompanying drawing, wherein

5 Fig. 1 is a perspective view of an assembled connector socket embodying my invention;

10 Fig. 2 is a similar view of one of the parts of the housing with the socket contact members in position;

15 Figs. 3, 4 and 5 are enlarged detail, perspective views of the parts of one of the contact members;

20 Figs. 6 and 7 are transverse sectional views 15 taken on the lines 6—6 and 7—7, respectively, of Fig. 2;

25 Figs. 8 and 9 are views similar to Fig. 7 but showing the position of the parts of one of the contact members or jacks of round and 20 rectangular cross-section, respectively; and

30 Fig. 10 is a detail transverse sectional view taken on the line 10—10 of Fig. 2.

In carrying out my invention as here embodied, 2 represents the casing or housing 25 formed of suitable insulating material and comprising the two halves 3 and 4 each of which is identical in size, shape and construction. Each of the halves has a pair of parallel spaced longitudinal contact member receiving recesses 5 the central portions of which are deeper than the side edges and the outer ends of these recesses communicate with notches of the same general outline but smaller in cross section so that when the two 35 halves of the casing are placed together said notches produce restricted mouths 6 leading to the recesses. The recesses 5 each communicate by means of a recess neck 7 with a chamber 8 in which rest the heads of the 40 socket contact members while from this chamber project the screw receiving cavities 9. A lead wire or cord receiving recess 10 is formed in the outer or rear end of each of the halves and is provided with diverging branches 11 45 leading to and communicating with each of the chambers 8 and the main portion or trunk of this recess is enlarged intermediate its ends to produce a spring receiving channel 12 which acts as a seat for a portion of the ordinary spring (not shown) used on lead wires 50 of connector sockets of this character. A frustoconical vent opening 13 is formed in each half so as to communicate with the recess 10 while straight bore vent openings 14 are 55 formed in each half in the region of the recesses 5 the latter being preferably two in number for each recess. The larger diameter of the vent openings 13 is on the inside of the housing member thus providing a large venti- 60 lating area in the interior without decreasing the strength of said housing member on its exterior.

65 Within each of the recesses 5 is located a socket contact member 15 approximating a parallelogram in cross section as shown in

Fig. 7, each of said socket contact members being slightly smaller than the recesses which they occupy so as to permit slight movements thereof for the reception of complementary contact members or terminals having varying 70 distances between centers.

Each of the socket contact members 15 comprises a stationary contact element 16 consisting of a flat body or contact section 17 having a longitudinal depression 18, forming, respectively, a flat contact surface 17' and a curved contact surface 18'. Parallel longitudinal side flanges or supports 19 extend upwardly from the opposite longitudinal side edges of the body 17, as shown in Fig. 4. 75 From one end of the body projects a restricted neck 20 connected with a head 21 having side flanges 22 and an end flange 23 to form a nut housing in the chamber of which is located a nut 24 the threaded bore of 80 said nut registering or aligning with a hole 25 in the aforementioned head and from the flanges 22 are produced the segmental arcuate lips 26, while the metal between the ends of said lips and the upper portions of the flanges produce webs 27 parallel with the head 21 and so overlap the nut 24 as to prevent the accidental withdrawal of the same. 85

90 Coacting with the stationary element is a pair of movable elements 28, one of which is shown in Fig. 10, and each of these consists of a flat body or contact section 29 having a flat contact surface 29'. Each of the contact sections 29 is provided with a side flange or support 30 along its outer edge, one end of which is bent inward as indicated at 31 so as to follow the outline of the projection 32 formed with the body 29, and said flange or abutment 30 has a portion cut away to 100 form a notch 33 for a purpose to be hereinafter described. From the inner edge of the body 29 projects the longitudinal parting flange 34, the parting flanges of the two movable elements engaging each other to 105 limit the inward movements of said elements. 110

115 The side flanges or abutments 30 of the movable elements 28 are fulcrumed upon the flanges or abutments 19 of the stationary element 16 so that said movable elements 28 having a swinging motion (Fig. 8) similar to a hinged object about one axis approximately parallel to the flat contact surfaces 29 thereof, and are forced toward the stationary member as well as being held assembled thereon by 120 means of the resilient member or spring 35 (Fig. 6) which is in the form of a jacket formed from a sheet of spring metal superimposed upon the stationary and movable elements throughout a portion of the length 125 and conforming approximately to their combined cross sectional shape, the said resilient member or spring being of a length equal to the notch 33 (Fig. 3) so as to fit therein and this resilient member or jacket has high resil- 130

ient qualities so as to produce a spring action upon the movable elements which with the stationary element are formed of metal having high conductivity regardless of its resilient properties and the action of this resilient member or spring is to force the elements into positive contact with the terminal member and this spring has no independent connection with the lead wire so that it has no bearing upon the construction other than to insure a positive electrical contact between the socket contact member and the complementary terminal.

When terminals, regardless of their shape are inserted between the elements of the socket contact member the movable elements will be opened parallel to the axis of the terminal throughout their entire length so that both of the movable elements and the stationary element will make a positive electrical contact throughout their entire length.

While I have shown only one form of embodiment of my invention, for the purpose of describing the same and illustrating its principles of construction and operation, it is apparent that various changes and modifications may be made therein, without departing from the spirit of my invention. I desire, therefore, that only such limitations shall be imposed thereon as are indicated in the appended claims or as are demanded by the prior art.

Having thus fully described my invention, what I claim as new and useful is:—

35 1. A jack-receiving socket, one side of which comprises a stationary contact element having flanges respectively positioned on opposite sides, another side of said socket having a pair of floating non-bending contact elements respectively provided with flanges positioned in close proximity to said first-mentioned flanges, and means for resiliently securing said contact elements in operative relation.

45 2. A socket comprising an elongated contact element having side flanges and a base portion adapted to engage a plug element of one form, a pair of contact elements positioned opposite to said base portion and provided with flanges respectively engaging said first-mentioned flanges, and a spring for holding said elements in assembled position, the adjacent edges of said pair of elements being separated substantially equally at all points when a plug is inserted in said socket.

55 3. A plug-receiving socket comprising a body having longitudinal flanges at the opposite side edges, movable elements having notched flanges on the outer edges thereof and parting flanges along the inner edges, said movable elements being fulcrumed on the stationary element with their flanges overlapping the flanges of said stationary element, and a spring positioned in said

notches for resiliently holding said elements in their assembled positions.

4. A socket contact comprising a stationary element having a main body portion and a projecting neck portion, flanges on the outer edges of said neck and body portions, a pair of bodily movable contact elements cooperating with said stationary contact element having side flanges formed complementary to the flanges of said stationary element, and resilient means for swingingly mounting said movable elements with the flanges thereof respectively overlapping the flanges of said stationary element.

5. In a jack-receiving socket, a plurality of independent full-floating, non-bending contact elements having elongated contact surfaces, at least one of said elements being freely movable with respect to another, and resilient means for uniting said elements with their contact surfaces substantially parallel, said means engaging at least one of said elements at a point intermediate the ends of its contact surface whereby said elements are relatively self-adjustable into positions parallel to the axis of a jack inserted longitudinally between the contact surfaces.

6. In a jack-receiving socket, a plurality of independent full-floating, non-bending contact elements having elongated contact surfaces, and resilient uniting means engaging said elements in circumferential relation intermediate the ends of their contact surfaces whereby said elements are relatively self-adjustable into positions parallel to the axis of a jack inserted longitudinally between the contact surfaces.

7. In a jack-receiving socket, a plurality of independent, non-bending contact elements having elongated contact sections, at least one of said elements being full-floating with respect to an opposed element, and resilient means for uniting said elements, said means engaging said full-floating element intermediate the ends of its contact surface whereby the elements are relatively self-adjustable to positions engaging with substantially uniform pressure throughout their lengths inserted jacks of different cross sectional dimensions.

In testimony whereof, I have hereunto affixed my signature.

THEODORE C. SMITH.
